HYDRAULICALLY CONTROLLED VARIABLE
PITCH PROPELLER

Heinrich Obrist, Zurich, Switzerland, assignor to
Escher Wyss Maschinenfabriken Aktiengesellschaft,
Zurich, Switzerland, a corporation of
Switzerland

Application July 11, 1945, Serial No. 604,476
In Switzerland August 5, 1944

8 Claims. (Cl. 60—52)

1

This invention relates to means for hydraulically controlling variable pitch propellers, particularly those for ships. The object of the invention is to provide means of this kind in which the hydraulic pitch-varying pressure can be obtained by means which, while being of a type of construction which is simple and reliable in action are entirely built into the propeller shaft. According to the present invention this is rendered possible by the fact that the casing of a servo-motor, which has a stationary piston, moves under the action of a liquid under pressure thereby effecting variation of the pitch of the propeller blades and is arranged in a portion of the propeller shaft which is constructed to form a cylinder, and that a pump which supplies the liquid under pressure required for shifting the servo-motor casing is arranged in the interior of the propeller shaft and is driven by an electromotor arranged within said shaft and adapted to rotate therewith. The pump which delivers the liquid under pressure may, in this type of construction, be built into the fixed or stationary servo-motor piston.

A constructional example of the subject matter of the invention is shown in a simplified mode of representation in the accompanying drawings in which:

Figs. 1a and 1b show the two halves of the axial longitudinal section through an arrangement for hydraulically varying the pitch of a propeller for propulsing a ship, the propeller being shown in elevation. In these figures the section is taken through the servo-motor on the line I—I of Fig. 2 and certain parts have been turned downwards in the plane of the drawing for the sake of clearness.

Fig. 2 shows on a larger scale a section on the line II—II of Fig. 1b through the servo-motor.

Fig. 3 is a section on the line III—III through a part of Fig. 2 and

Fig. 4 shows on a larger scale a section on the line IV—IV of Fig. 1b.

In the drawings, 1 denotes a propeller fitted with blades the pitch of which is to be varied and which serves to drive a ship. This propeller is operatively connected through a hollow shaft 2, a cover 3 which forms a whole with the latter, a part 4 constructed to form a cylinder and closed on the left hand side by said cover 3, and a further cylinder 5, to a driving shaft 11, the parts 2, 3, 4, 5 and 11 being rigidly connected so as to rotate as a unit. The hollow shaft 2, the cover 3 and the cylinders 4, 5 form together what is termed in this specification the propeller shaft. 55

2

The cylinder 6 of a servo-motor is arranged in the cylindrical part 4 in such a way that it will slide therein. The piston of this servo-motor comprises a piston body 6¹ proper and a second part 6² connected thereto by studs, as shown. This latter is connected by means of an extension 9 to a cover 10 which is clamped between the cylinders 4 and 5 in such a way that the piston 6¹, 6² is prevented from making any axial movement. At its right hand end the servo-motor cylinder 6 is closed by a cover 6³. The reference 15 denotes an adjusting spindle which is rigidly connected to the cylinder 6 of the servo-motor. The adjusting spindle 15 is coupled to a rod 16 which in its turn is connected mechanically to a mechanism 14 for varying the pitch of the blades of the propeller 1. The two spaces on either side of the servo-motor piston 6¹, 6² are denoted by 7 and 8. These spaces 7 and 8 and the hollow space 4¹ in the cylindrical part 4 of the propeller shaft, which is not taken up by the servo-motor, are filled with a liquid, preferably oil. A pressure considerably above atmospheric pressure prevails temporarily in the spaces 7 and 8 during the occurrence of the adjustment of the blades, while in the space 4¹ prevails at all times a pressure which is only slightly greater than the atmospheric pressure.

In the parts 6¹, 6² of the piston is mounted a toothed wheel 12 which cooperates with a second toothed wheel 13. These two wheels 12 and 13 constitute a pump which is driven through a shaft 17 and a toothed coupling 18 by an electromotor 19. This latter is arranged within the cylinder 5 of the propeller shaft, and is fast therein and rotates with it. For sealing the shaft 17 at the right hand end of the extension 9 a sealing device is provided which comprises two sealing rings 17² and a spring 17¹, the latter tending to force these rings against sealing seats. This sealing device is the only sealing means working under a pressure above atmospheric pressure that has to be provided on the side at which the energy needed for the adjustment of the blades is supplied. The embodiment described also realizes the advantage that the diameter of said sealing device 17¹, 17² can be relatively small and that this device is exposed to a pressure above atmospheric only during the occurrence of a pitch variation. Thus, the sealing problem on the side at which the supply of energy takes place is solved in a manner which ensures a minimum of oil losses.

20 denotes an intermediate member which is clamped fast between the cover 3 and the cylin-

der 4, and 21 denotes a toothed wheel arranged within the cover 3, this toothed wheel 21 being operatively connected by means of a quick-pitch multiple screw thread 15¹ with the adjusting spindle 15 and held in its axial position by bearings 22, 23. The intermediate member 20 has a cylindrical extension 20¹ in which a piston 24 compelled to rotate with the members is slidably arranged. This piston 24 is acted upon by a helical spring 27 tending to urge it towards its left hand terminal position, in which it then holds fast the toothed wheel 21 by means of a locking member 25 rigidly connected to the piston 24. In the left hand end of the cover 3 is mounted a sleeve 26 provided with a bore of square section and with an extension 26¹, a portion of the latter being screw-threaded. In case of necessity the position of the blades of the propeller 1 can be varied whilst the latter is at a standstill by rotating said sleeve 26 by hand. Any such rotation involves a throwing out of the locking member 25, which is in operative connection with a nut 26² co-operating with the screw-threaded portion of said extension 26¹ of the sleeve 26. As soon as the member 25 has been thrown out of its locking position, a shaft 28 which is supported in the left hand end of the cover 3 and in the member 20 and which comprises both a bore of square section and a toothed rim 28 is operated from outside in order to rotate the toothed wheel 21 meshing with said rim 28. The wheel 21 then operates the adjusting spindle 15 connected to the mechanism 14 for varying the pitch of the propeller blade. 33 denotes a pipe rigidly connected to the servomotor piston part 31 (Fig. 3) and communicating through a slot 34 (Fig. 1b) with the space 4¹ on the left hand side of the servomotor 6, 6¹, 6², 6³. This pipe 33 is connected through a second slot 34¹ (Figs. 3 and 4) with a passage 35, which opens into a space 36. The pipe 33 surrounds a pipe 30 which, as shown in Fig. 3, is rigidly connected to this pipe 33 and communicates with a groove 31 in the part 6² of the servomotor piston, this groove 31 communicating in its turn with two recesses or cavities 32, 32¹ (Figs. 3 and 4). The pipe 30 opens at its left end into a space connected through a duct 30¹ (Fig. 1b) with a pressure space 30² allotted to the piston 24. As is shown in Fig. 2, the pipe 33 has symmetrically opposite a second pipe 33¹ communicating through a slot, which corresponds to the above mentioned slot 34 and is therefore not shown in the drawings, with the space 4¹ on the left hand side of the servomotor 6, 6¹, 6², 6³. Two movable piston valves 37 and 38 (Fig. 2) are arranged within the space 36, each of which has an opening 37¹ and 38¹ respectively. A spring 40 arranged between these piston valves 37 and 38 tends to move them away from each other. The piston valve 37 controls the communication between the space 36 and a passage 41. This latter communicates with a passage 42 which opens into the servomotor space 8. The piston valve 38 controls in its turn the communication between the space 36 and a passage 43 (Figs. 2 and 3), which communicates with a passage 44 opening into the servomotor space 7. 45 and 46 (Figs. 2 and 4) denote two spaces provided in the part 6¹ of the servomotor and which fulfill temporarily the functions of a suction or pressure space according to the direction in which the pump toothed wheels 12, 13 rotate. Communication between the interior of the pipe 33 and the space 45 is controlled by a flap valve 47 and communication between the interior of

the pipes 33¹ and the space 46 is controlled by a flap valve 48. 49 and 50 (Fig. 2) denote spring-loaded excess pressure valves, which when they lift, enable liquid under pressure to pass through bores 51 and 52 (Fig. 4) in that of the spaces 8 and 7 respectively in which at the moment no pressure above atmospheric pressure prevails.

53 (Fig. 1b) denotes a resistance coil against which bears a sliding contact 54 rigidly connected to the cover 6³ of the servomotor by means of a rod 54¹. The sliding contact 54 is thus compelled to effect the same movements as the casting 6 of the servomotor. The coil 53 is connected by electric conductors to slip rings 56 and 57 and the sliding contact 54 is connected to a slip ring 55. The references 58 and 58¹ denote two further slip rings, which, together with the slip ring 56 permit current to be supplied from a main x, y, z to the electromotor 19. 59 denotes a brush carrier, which permits of connection being established between the revolving and the stationary parts of the electrical arrangement, said brush carrier being also connected electrically to a controlling switch 61 provided with a handle 60. The arrangement is such that when the handle 60 is moved towards the right, the electromotor 19 runs in the opposite direction to that in which it runs when the handle 60 is moved towards the left. The direction of rotation of the electromotor 19 also determines the direction of the pump wheels 12 and 13. Finally 62 denotes an indicating instrument, which is acted upon indirectly by the resistance coil 53 and furnishes information as to the particular position 35 of the propeller blades at the moment. In addition to this electrical position-indicating arrangement a mechanical indicating arrangement, to which parts 70 and 71 belong, is also provided.

60 The way in which the arrangement for hydraulically varying the pitch of the blades of the propeller works is as follows:

Assuming that the controlling switch 61 has been moved into such a position that the electromotor 19 rotates the pump wheels 12, 13 in the direction indicated by the arrows in Fig. 2, the space 45 will act as a suction space and the space 46 as a force or delivery space. The suctional action set up in the space 45 causes the flap valve 47 to lift, so that communication between the interior of the pipe 33 and the suction space 45 is established. The result of this is that the pump 12, 13 draws oil through the slot 34 out of the space 4¹ on the left hand side of the servomotor 6, 6¹, 6², 6³. The liquid under pressure delivered by the pump 12, 13 into the space 46 passes through a passage 63 (Fig. 2) to the right hand end face of the piston valve 37, so that this latter is pushed towards the left. Oil under pressure passes into an annular groove 37² and from the latter through the recess 32 and groove 31 into the pipe 30, and consequently into the pressure space 30² allotted to the piston 24, so that the latter is pushed towards the right and thereby causes the releasing of the toothed wheel 21 which can now be rotated. As the pump pressure continues to increase, the piston valve 37 will be pushed still further to the left so that it finally establishes communication between the passage 63 and the passage 41, with the result that oil under pressure passes out of the space 46 into the passage 42 and thence into the space 8 within the servomotor. This causes the servomotor casting 6 to move towards the right, the adjusting spindle 15 also being carried along with it. The result of all this is that the blades of the propeller

I will have their pitch varied by a definite amount in one direction. On the above mentioned movement of the servomotor casing 6 towards the right the oil contained in the space 7 will be forced through the passage 44 and the passage 43 and through the opening 38¹ into the space 36, out of which it can run off through the passage 35 and the slot 34¹ into the pipe 33, to be either drawn in again by the pump 12, 13 or allowed to run off through the slot 34 into the space 4¹ on the left hand side of the servomotor 6, 6¹, 6², 6³.

When the desired variation in the pitch of the blades of the propeller has been effected, the controlling switch 61 is moved back into its neutral position, whereupon the pump 12, 13 ceases to deliver. The spring 27 is now in a position in which it can move the piston 24 towards the left so that the wheel 21 is locked again and the propeller blades consequently secured in their new position.

When the controlling switch 61 is moved over into the opposite position the servomotor cylinder 6 can be moved towards the left and a change in the pitch of the propeller blades is effected in a direction opposite to that mentioned above. In this case the annular groove 38² and the passage 63¹ fulfill the same functions as the groove 37² and the passage 63 fulfilled in the previous case.

Should the pump fail to act for any reason or should a breakdown in the supply of current occur, the arrangement described makes it possible to bring the blades of the propeller into any desired position by hand after the arrangement has been stopped for a short time. As soon as this is the case, the sleeve 26 is turned by a ratchet key in such a way that the locking device 25 on the piston 24 is brought out of the position in which it locks the toothed wheel 21. By means of the same ratchet key the shaft 29 and with it the toothed wheels 28 and 21 can be turned to the extent required for bringing the blades of the propeller into the exact position desired.

The amount by which the pitch of the blades of the propeller 1 has been varied can be ascertained at any time by reference to the indications furnished by the indicating instrument 62. When the pitch of the blades of the propeller is effected by hand, the arrangement 70, 71 may conveniently be used for ascertaining the position of the propeller blades. This latter arrangement also enables the electrical position indicating instrument 62 to be controlled at the same time.

For the sake of completeness it may be mentioned that 64 and 64¹ denote two oil supply casings of which the casing 64 communicates through a pipe 65 with an oil storage chamber 66, so that the oil pressure prevailing in the interior of the propeller hub is always greater than the pressure which the water exerts from the outside. The casing 64¹ is also connected with an oil storage chamber, which however has not been illustrated so that all parts within the hub and the hollow shaft of the propeller are continuously subjected to an oil pressure of a certain magnitude.

The invention may also be used in connection with screw propellers which are used to drive aircraft.

What is claimed is:

1. A self-contained adjusting assembly for interposition as a unit between two coaxial rotary shafts, one of which drives the other and one of which includes an internal axially shiftable adjusting member, said unit comprising, a generally cylindrical housing having at its oppo-

site ends means for torque-transmitting connection to respective ones of said alined shafts; means subdividing said housing into a sump and a motor chamber; a double-acting expansible chamber hydraulic motor in said sump said motor having two opposed working spaces and means for connection with said axially shiftable adjusting member; a reversible pump; pressure operated valve means biased to a position in which they connect said two working spaces with said sump, said valve means serving selectively in response to pressures developed by reverse operations of said pump, to isolate respective working spaces of the motor and subject the isolated working space to the pressure so developed; a reversible electromotor in said motor chamber connected to drive said pump; releasable means biased to lock said hydraulic motor; and means serving to release said locking means upon operation of said electromotor in either direction.

2. The combination defined in claim 1 in which the pump is located in the sump, the connection between said electromotor and pump passes through said subdividing means and makes a liquid-sealed joint therewith, the means for connection of the hydraulic motor with said axially shiftable adjusting member comprises a shaft which extends through the sump and thence through a packed bearing to the adjusting member, and means are provided to maintain the sump under a moderate hydraulic pressure.

3. The combination defined in claim 1 in which the double-acting motor comprises a fixed piston and an axially slidale cylinder having means for direct connection to the axially shiftable adjusting member, the pump and pressure operated valve means are mounted in the piston, and the piston is sustained by said subdividing means.

4. A self-contained adjusting assembly for interposition as a unit between two coaxial rotary shafts, one of which drives the other and one of which includes an internal axially shiftable adjusting member, said unit comprising, a generally cylindrical housing having at its opposite ends means for torque-transmitting connection to respective ones of said alined shafts; means subdividing said housing into a sump and a motor chamber; a double-acting expansible chamber hydraulic motor in said sump and arranged for connection with said axially shiftable adjusting member; a reversible pump with automatic reversing valve means arranged to draw liquid from said sump and deliver it under elevated pressure selectively to one or the other working space of said double-acting motor according to the direction in which the pump is driven; a reversible electromotor in said motor chamber and connected to drive said pump; engageable means for locking said hydraulic motor against motion; means biasing said locking means to engaged position; and pressure operated means responsive to the elevated pressure developed by operation of said pump in either direction and serving to disengage said locking means.

5. A self-contained adjusting assembly for interposition as a unit between two coaxial rotary shafts, one of which drives the other and one of which includes an internal axially shiftable adjusting member, said unit comprising, a generally cylindrical housing having at its opposite ends means for torque-transmitting connection to respective ones of said alined shafts; means subdividing said housing into a sump and

a motor chamber; a double-acting expansible chamber hydraulic motor in said sump and arranged for connection with said axially shiftable adjusting member; a reversible pump with automatic reversing valve means arranged to draw liquid from said sump and deliver it under elevated pressure selectively to one or the other working space of said double-acting motor according to the direction in which the pump is driven; a reversible electromotor in said motor chamber and connected to drive said pump; a rotary member arranged to be rotated by the hydraulic motor; a clutch engageable to lock said rotary member against rotation; yielding means urging said clutch to engaging position; and pressure operated means responsive to the elevated pressure developed by operation of said pump in either direction to disengage said clutch.

6. A self-contained adjusting assembly for interposition as a unit between two coaxial rotary shafts, one of which drives the other and one of which includes an internal axially shiftable adjusting member, said unit comprising, a generally cylindrical housing having at its opposite ends means for torque-transmitting connection to respective ones of said aligned shafts; means subdividing said housing into a sump and a motor chamber; a double-acting expansible chamber hydraulic motor in said sump and arranged for connection with said axially shiftable adjusting member; a reversible pump with automatic reversing valve means arranged to draw liquid from said sump and deliver it under elevated pressure selectively to one or the other working space of said double-acting motor according to the direction in which the pump is driven; a reversible electromotor in said motor chamber and connected to drive said pump; a gear arranged to be rotated by the hydraulic motor; a clutch engageable to lock said gear against rotation; yielding means urging said clutch to engaging position; pressure operated means responsive to the elevated pressure developed by operation of said pump in either direction to disengage said clutch; and two means manually operable at points external to said housing when the latter is at rest, the first of which comprises mechanical means for holding said clutch disengaged and the second of which comprises mechanical means for rotating said gear.

7. A self-contained adjusting assembly for interposition as a unit between two coaxial rotary shafts, one of which drives the other and one of which includes an internal axially shiftable adjusting member, said unit comprising, a generally cylindrical housing having at its opposite ends means for torque-transmitting connection to respective ones of said aligned shafts; means subdividing said housing into a sump and a motor chamber; a double-acting expansible chamber hydraulic motor in said sump and comprising a piston fixedly supported by said subdividing means and a double-acting cylinder slidable on said piston and its support, divided by the piston into two working spaces and adapted for connection with said axially shiftable adjusting member; a reversible pump mounted in said piston; pressure operated valve means biased to a position in which they connect said two working

spaces with said sump, said valve means being mounted in said piston and serving selectively, in response to pressures developed by reverse operations of said pump, to isolate respective working spaces of the motor and subject the isolated working space to the pressure so developed; a reversible electromotor housed in said motor chamber and mechanically connected with said pump through said subdividing means and the related piston support; releasable means biased to lock said hydraulic motor; and means serving to release said locking means upon operation of said electromotor in either direction.

8. A self-contained adjusting assembly for interposition as a unit between two coaxial rotary shafts, one of which drives the other and one of which includes an internal axially shiftable adjusting member, said unit comprising, a generally cylindrical housing having at its opposite ends means for torque-transmitting connection to respective ones of said aligned shafts; means subdividing said housing into a sump and a motor chamber; a double-acting expansible chamber hydraulic motor in said sump and comprising a piston fixedly supported by said subdividing means and a double-acting cylinder slidable on said piston and its support and adapted for connection with said axially shiftable adjusting member; a reversible pump with automatic reversing valves arranged to draw liquid from said sump and deliver it under elevated pressure selectively to one or the other working space of said double-acting motor according to the direction in which the pump is driven, said pump and valves being housed in said piston; a reversible electromotor housed in said motor chamber and mechanically connected with said pump through said subdividing means and the related piston support; engageable means for locking said hydraulic motor against motion; means biasing said locking means to engaged position; and pressure operated means responsive to the elevated pressure developed by operation of said pump in either direction and serving to disengage said locking means.
